(57) **CLAIM**

The ornamental design for an information handling system as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a front perspective of the information handling system in an open position;

FIG. 10 is a front perspective view of the information handling system in a tent position; and

FIG. 11 is a rear perspective view of the information handling system in a tablet position.

FIG. 12 is a detailed view of the information handling system as identified in FIG. 3;

FIG. 13 is a detailed view of the information handling system as identified in FIG. 8;

FIG. 14 is a detailed view of the information handling system as identified in FIG. 9;

FIG. 15 is a detailed view of the information handling system as identified in FIG. 10;

FIG. 16 is a detailed view of the information handling system as identified in FIG. 11; and,

FIG. 17 is a detailed view of the information handling system as identified in FIG. 11.

The broken lines depict portions of the information handling system that form no part of the claimed design.

1 Claim, 15 Drawing Sheets
